UNITED STATES PATENT OFFICE.

HARRY H. JONES, OF FULLERTON, CALIFORNIA.

HYDRAULIC WELL-TOOL ACTUATOR.

Application filed July 14, 1924. Serial No. 726,062.

To all whom it may concern:

Be it known that I, HARRY H. JONES, citizen of the United States, and resident of Fullerton, in the county of Orange, State of California, have invented new and useful Improvements in a Hydraulic Well-Tool Actuator, of which the following is a specification.

This invention relates to a device for actuating at will instruments by hydraulic means. More particularly, this invention pertains to the manipulation of instruments in holes by means of hydraulic pressure exerted by liquid contained therein, which liquid is normally used for other purposes.

The present invention is especially adaptable for use in hydraulic drilling of wells.

In hydraulic drilling of wells it is often desirable to manipulate tools within the hole, for illustration, to expand and contract reamers, underreamers, fishing tools, pipe cutters and splitters, and the like. These functions are now commonly performed by means of springs, cables, and weighted parts, thereby being limited in their adaptability. The embodiment of the present invention disclosed herein is designed to employ the pressure of slush or circulation liquid in the drill piping, tubing or casing of oil wells, so as to actuate an instrument or tool located within the well remote from the surface. The primary object of this invention is to provide an instrument of the character described, which is simple, durable, and compact.

These objects together with other objects and corresponding accomplishments are obtained by means of the embodiment of my invention illustrated in the accompanying drawing, in which:

Fig. 1 is an axial section through an actuator connected to a string of drill pipe; and Fig. 2 is a section as seen on the line 2-2 of Fig. 1.

Referring more particularly to the drawing, a section of drill pipe 3 has a coupling 4 of special construction connecting it to a conduit or tubular barrel 5. Another coupling 6 of special construction is secured to the bottom of barrel 5 and serves for attaching the tool to be operated or fittings disposed intermediate the tool and actuator. The bore of coupling 4 is reduced in diameter at the center and internally threaded to receive a plug 7. The lower end of the reduced portion is also internally threaded

to receive a cylinder 8 which is secured thereto. The cylinder 8 is of such external diameter that an annular space or passage 9 is provided between the drill pipe 4 and the cylinder. Extending through the couplings are passages 10 communicating with the space within the drill pipe above the actuator and with the space 9. Extending through the coupling from the exterior to the bore thereof are ducts 11. These ducts communicate with the bore at a tapered plunger guide portion below the plug 7 and place the upper part of the bore of the cylinder in communication with the exterior of the drill pipe.

Coupling 6 has a bore of reduced diameter providing a slip fit with the cylinder 8, the latter extending below the coupling. Longitudinally extending passages 12 place the annular chamber 9 in communication with the bore of the tool or fitting connected thereto. The aggregate cross-sectional area of passages 12 is less than that of passages 10 in coupling 6.

A head 13 is screwed into the lower end of cylinder 8 and is provided with a bore and a stuffing box 14 through which may slidably extend the plunger connecting member 15. The cylinder 8 has its bore in communication with the annular chamber 9 through ports 16. Mounted upon the rod 15 is a plunger 17 of suitable design.

The present invention is in no way limited to the character of the tool to be manipulated. The tool is connected by suitable fittings to the coupling 6. Assume that the tool is an expandable reamer, wherein the reamer cutters are to be expanded when the tool has reached its working position. The rod 15 will be connected to the actuating member of the tool by means of suitable linkage. Circulation is maintained down through the drill pipe, the liquid passing from the drill pipe through passages 10 to annular chamber 9 and from there on through passages 12, and thence in the usual path to the tool.

The parts are so arranged that plunger 17 will be positioned in the lower portion of the cylinder above ports 16 when there is no pressure of liquid in the drill pipe or the pressure is low. This is the position of the parts while the tool is being lowered to working position. After the tool has reached its working position, the slush pumps are started, thereby creating a pres-

- 2
- 5 pressure in the annular chamber 9. This pressure is transmitted to the lower side of plunger 17 through ports 16 in the cylinder. Pressure above the plunger 17 is less due to the pressure on the outside of the drill pipe. Because of this difference in pressure, the plunger 17 will be moved upwardly and actuate the tool. When the pump pressure is relieved preparatory to pulling the drill 10 pipe and tool, the pressure on opposite sides of the plunger will be equalized and the weight and pull of the parts upon the plunger rods 15 will cause the plunger to be moved downwardly.
- 15 It is obvious that by reversing the points of inlet and outlet of the fluid, the plunger can be operated by the pressure so as to be pushed downwardly instead of upwardly. By making the passages 12 small and few in 20 number as compared with the passages 10, liquid entering from below when the drill pipe is being lowered causes little or no pressure to be applied to the plunger. On the other hand, when the pump is placed 25 in operation, because of the small area of the openings in the bottom coupling, a pressure is at once created which acts directly on the plunger, raising or pushing down as the case may be.
- 30 What I claim is:
1. In combination with a conduit, spaced coupling members therein, a cylinder mounted between said coupling members forming an annular chamber between said conduit and cylinder for the passage of fluid about said cylinder, said coupling members having ducts extending therethrough, and a reciprocable piston mounted in said cylinder, one end of said cylinder 35 communicating with a source of low pressure and the other end of said cylinder communicating with said passageway.
  2. In combination with a conduit, spaced coupling members therein, a cylinder mounted between said coupling members forming a chamber between said conduit and cylinder for the passage of fluid about said cylinder, said coupling members having ducts extending therethrough, and a reciprocable piston mounted in said cylinder, one end of said cylinder 40 communicating with the exterior of said conduit and the other end of said cylinder communicating with said passageway.
  3. In combination with a conduit, spaced coupling members therein, a cylinder mounted between said coupling members forming a chamber between said conduit and cylinder for the passage of fluid about said cylinder,
- 45
- 50
- 55
- 60 cylinder, coupling members having ducts extending therethrough, the aggregate cross-sectional area of the lower ducts being less than that of the upper ducts, and a reciprocable piston mounted in said cylinder, one end of said cylinder communicating with a source of low pressure and the other end of said cylinder communicating with said passageway.
- 65
- 70
- 75
- 80
- 85
- 90
- 95
- 100
- 105
- 110
- 115
4. In combination with a conduit, spaced coupling members in said conduit, a cylinder mounted between said coupling members forming a chamber between said conduit and said cylinder for the passage of fluid about said cylinder, coupling members having ducts extending therethrough, the aggregate cross-sectional area of the lower ducts being less than that of the upper ducts, and a reciprocable piston mounted in said cylinder, one end of said cylinder communicating with the exterior of said conduit, and the other end of said cylinder communicating with said passageway.
5. In combination with sections of tubing, spaced coupling members secured to the ends thereof, a cylinder secured to and between said coupling members so as to form an annular chamber for the passage of fluid about said cylinder, heads closing the ends of said cylinder, said couplings have ducts extending longitudinally therethrough, one of said coupling members having transverse ports connecting the bore of said cylinder at one end with the exterior of said tubing, said cylinder communicating with said chamber at the other end, and a reciprocable piston mounted in said cylinder.
6. In combination with sections of tubing, spaced coupling members secured to the ends thereof, a cylinder secured to and between said coupling members so as to form an annular chamber for the passage of fluid about said cylinder, heads closing the ends of said cylinder, each of said couplings having ducts extending longitudinally therethrough, the aggregate cross-sectional area of the ducts being less in the lower coupling than that in the upper coupling, one of said coupling members having transverse ports connecting the bore of said cylinder at one end with the exterior of said tubing, said cylinder communicating with said chamber at the other end, and a reciprocable piston mounted in said cylinder.
- In witness that I claim the foregoing I have hereunto subscribed my name this 26th day of June, 1924.
- HARRY H. JONES.
